[57] CLAIM

The ornamental design for a children's block table, as shown and described.

DESCRIPTION

FIG. 1 is a top perspective view of a children's block table showing my new design;

FIG. 2 is an additional top perspective view of said table thereof with children's blocks thereon;

FIG. 3 is a side elevational view of said table;

FIG. 4 is a top view of said table;

FIG. 5 is a bottom perspective view of said table;

FIG. 6 is a perspective view of a leg assembly removed from said table; and,

FIG. 7 is a detailed bottom perspective view of said table with the leg assembly shown in FIG. 6 removed therefrom.

The broken line showing of the pockets is for environmental purposes only and forms no part of the claimed design.
